UNITED STATES PATENT OFFICE.

ROBERT J. SHEEHY, OF NEW YORK, N. Y.

SELECTING AND SIGNALING SYSTEM.

No. 831,687.

Specification of Letters Patent.

Patented Sept. 25, 1906.

Application filed October 9, 1902. Serial No. 126,507.

To all whom it may concern:

Be it known that I, ROBERT J. SHEEHY, a citizen of the United States, residing in the city, county, and State of New York, have invented certain new and useful Improvements in Electric Selecting and Signaling Systems, of which the following is a specification.

This invention relates more especially to railroad and municipal telegraph and signaling systems and to any system wherein it is desired to communicate with one or more stations on a circuit to the exclusion of others.

It comprehends an organization in which the central or main office operator may at pleasure select and connect his apparatus with any one of several instruments in the circuit, and as secondary to this operation at the time of such selection one or more characters of automatic signals may be displayed or thrown into operation at the selected substation.

The invention further consists in an organization having the following characteristics: First, a telegraphic instrument of any desired character—such, for instance, as a Morse outfit, a recorder or printing telegraph or telephone may be connected into the circuit at the selected station, corresponding instruments being available at the central or main station; second, upon the selection of any one of a number of stations on the line the selected station when called sends automatically to the central office a return-signal indicating that the desired station has been properly selected and is ready for communication; third, the central-office operator may successively select one, two, or more stations upon the line and place them in communication with each other and with the central office; fourth, the central-office operator may at will simultaneously introduce the instruments at all of the stations into the line-circuit for communication of general orders; fifth, each station may be provided with an emergency call by which the operator at any one station in case of accident or other emergency may instantly communicate with the central office irrespective of the condition of the circuit and of the connection of the central-office instruments with other stations; sixth, the condition of the circuit is automatically indicated at each station, so that the individual operators at the several stations may know whether or not the line is free for their use.

In carrying out the invention I employ currents of alternating polarity. All the instruments being normally at unison, the station selected in any given instance is determined by the number of alternating impulses transmitted to bring the apparatus of the desired station to such point as to properly connect its instruments for communication with those at the central office. Whenever a station is thus selected, the central-office apparatus comes to rest always with a given pole of the main battery to line. As shown in the drawings, it is the negative pole. When communication between a selected station and the central office has been completed, the operator may transmit over the line a sufficient number of impulses to bring all the instruments to the unison-point, or he may select any other station by transmitting a sufficient number of alternating impulses to bring the apparatus of the desired station into position to introduce its instruments in the line. Whenever a station is selected, the automatic apparatus there located sends to the central office a return-signal, which may be the number by which the station is designated, to advise the operator that the proper station has been selected, so that he may proceed with his communication, the proper telegraph apparatus having at the same time been introduced into the line at the selected station. In some instances, and more especially in railroad-work, it is desirable that the central-office operator should be able at the time of selecting any one station to automatically display there a signal. This enables him to act promptly and give necessary signals at a substation without waiting to communicate with the operator at the selected station. I provide an arrangement whereby the central-office operator is enabled to bring the apparatus of any substation into two positions, in one of which a safety-signal is automatically displayed and in the other a danger-signal, and in either case the telegraphic apparatus at the selected station is introduced into the circuit. In the event of circumstances arising rendering it desirable for the despatcher or central-office operator to simultaneously introduce all of the stations on the line if it is only necessary for him to arrest his apparatus with the positive pole of the main battery to line. The armature-levers of the polarized instruments at all the substations then pause upon the stops other than those.

on which they pause when the stations are being selected. The polarized instruments in that event control circuit connections that introduce into the line the instruments at all the stations, and in connection with this operation at each station a signal may be sounded or displayed to call the attention of the operators or for any other purpose.

If the pole-changing apparatus at the central station is constructed to send to line thirty impulses of alternating polarity, there would be fifteen impulses of each polarity transmitted for each revolution of the shaft of the master instrument, and in order to make proper selection of substations and operate their telegraphic apparatus I make use of fourteen impulses of negative polarity. This permits seven substations on the line, each station having two numbers or points of rest. The fifteenth impulse of negative polarity, which would be the last impulse given by the pole-changing device, is utilized as a point of rest for the entire apparatus in circuit, and when switch 15 is plugged the apparatus at all stations will be at the zero-point and a "clear" signal displayed at each station.

In event of any one or more of the substation apparatus getting out of step with the master instrument the despatcher or central-office operator can bring all instruments to unison by allowing the shaft of the master instrument to make, say, three revolutions and then insert plug in switch 15, the shafts in the devices at the substations being arranged to go to unison on two revolutions. On the other hand, if it is desired that the apparatus at each substation shall be brought to a single position only, then with thirty alternating impulses in a revolution of the shaft of the pole-changer there may be fourteen substations on the line, and in such case the fifteenth position in which the apparatus pauses with the negative pole of the battery to line may be utilized to set all the instruments at unison and to automatically display in each substation a signal indicating to the operator that the line is clear.

In the accompanying drawings I have illustrated the invention in a form which experience has demonstrated to be efficient and satisfactory. Obviously, however, the details of the instruments as well as general circuit connections may be modified by those skilled in the art without departing from the invention.

Figure 1 is a diagrammatical view illustrating the central or despatcher's office apparatus; Fig. 2, a similar view of one station, which is No. 6.

As shown, the apparatus is arranged for seven stations.

In Fig. 1, MB indicates a main battery, and L the line, which may be grounded or connected to a return-conductor at the cen-

tral station. The coils of the polarized relay PR are included in the line, and the main battery is reversed by an automatically-acting pole-changer, a convenient form of which is as follows: Insulated pole-changer contacts *a a*, with which the sides of the line are connected, are carried upon an escapement-lever B, alternately actuated in opposite directions. The pole-changer contacts operating in connection with contacts connected with the main battery successively reverse the current on the line. The escapement-lever B is alternately acted upon by two magnets C C' and drives the shaft C². A trailer C³ on this shaft sweeps a circle of segments, the alternate ones of which are insulated from each other and are connected with plug-contacts. Segment 1 is connected by wire *x* with plug-contact 1²; segment 1', by wire *x'* with plug-contact 1³. The plug-contacts 1² and 1³ are arranged on opposite sides of a contact-block 1⁴, connected by wire *y*, with stop *z'* of the main line relay PR, upon which the relay armature-lever remains when the negative pole of the battery is left to line. In like manner the succeeding segments, as 2 and 2', 3 and 3', &c., are respectively connected with the plug-contacts of the plug-switches 2 3, &c., the central contact-block in each plug-switch is connected in like manner by wire *y* with the relay-stop *z'*. The fifteenth of these insulated segments is connected by wire *x'* with a plug-contact 15², the companion contact 15² of which is connected by wire *y* with the stop *z'* of the relay. The fifteen intervening segments are connected together, being shown in the drawings as teeth projecting from a single plate, and from a point marked 16 a wire *x*³ connects them with a plug-contact 16², the companion contact 16² of which is connected by wire *z* with relay-contact *y'*, upon which the relay armature-lever remains when the positive pole of the battery is left to line. A local battery LB has one pole connected through the escapement-magnet C to the relay-stop *z'* and by a branch circuit through the escapement-magnet C' with the other contact-post *y'* of the relay. The opposite pole of this battery is connected with armature-lever of the relay PR and by wire *z'* with trailer C³. If now all of the plug-switches are unplugged, it will be obvious that the automatic rotation of the shaft C² will continuously take place, and with the vibrations of the escapement-lever the main battery will be reversed upon the line each time that the trailer passes from one segment to another. If, however, switch 15 is plugged, as shown in the drawings, the apparatus will be brought to rest with the armature of the polarized relay PR upon its contact *y'* and the negative pole of the battery will remain to line. Current from battery LB will then be directed through magnet C'; but, the switch 15 being plugged,

when the trailer comes in contact with segment 15 the circuit of battery LB is completed through magnet C, and, owing to the close proximity of the armature to its core, 5 the escapement-lever 16 will be held in the position shown and the negative pole of main battery will remain to line. On removing the plug from switch 15 the circuit of magnet C will be broken and magnet C' 10 will attract its armature, moving the escapement-lever and causing a reversal of the main battery, upon which armature-lever of polarized relay PR will pass to its contact-stop z', thereby transferring the current from 15 magnet C' to magnet C and causing the escapement-lever to be moved in the opposite direction to advance the trailer C'.

When switch 16 is plugged, the armature of magnet C' will be held down and the positive pole of the main battery will remain to line. This is the condition made use of to introduce the apparatus at all the stations into circuit. When switch 15 is plugged, the position of the apparatus is that corresponding 25 with unison at all of the instruments, and in this position a clear-signal is displayed at all of the stations. If it is desired, for instance, to select station No. 6, the central-office operator puts a plug into the plug-switch 6 and then removes the plug from the unison-switch 15. The automatic movement of the trailer then commences, and the main battery is reversed as it passes from segment to segment. When the trailer 35 reaches the segment marked 6, twenty impulses of alternating polarity will have been thrown upon the line. If the plug has been inserted into the left hole in the switch 6, the polarized relay will remain upon its contact 40 y', and the instrument will be brought to rest, twenty-two alternating impulses having been transmitted to bring the apparatus of station 6 into one of the positions to which it is capable of being brought. If the plug had been inserted into the right-hand hole, the trailer would have continued its movement to the contact 6' and twenty-four alternating 45 impulses would have passed over the circuit and the apparatus at station 6 would have 50 been brought into its second position. In either case the instruments at station 6 will be introduced into the circuit and a signal displayed, the character of the signal depending upon the position of the apparatus at the 55 selected station. In similar manner any one of the seven stations may be selected and brought into either of the two positions desired. At any time the apparatus at all stations may be brought to the unison-point by 60 removing the plugs from the station-switches and plugging the unison-switch 15.

It is obvious that instead of the driving escapement such as illustrated in Fig. 1 any other well-known form of escapement may 65 be employed.

If the central-office operator plugs the switch 16, which is connected with the fifteen segments intervening between the insulated segments, then whenever the trailer comes upon one of these fifteen segments the armature-lever of the polarized relay PR remains 70 upon its stop z', the positive pole of the battery will remain to line, and the polarized instruments at all of the stations will similarly remain upon the corresponding stops. Under 75 these conditions the instruments at all the stations are automatically introduced into circuit and may all simultaneously receive communications from the central office or from any station. 80

I have shown two classes of telegraphic apparatus in the central or despatcher's office, one an ordinary printer controlled by a relay and the other a Morse set having both a sounder and a recorder, either of which may 85 be used, the instrument being operated by an ordinary neutral relay, as shown. An ordinary Morse key is placed in the circuit for transmission to any of the stations. At each substation, as at station 6, represented in 90 Fig. 2, the line passes through an emergency-call box and the coils of the polarized relay PR³ to a spring-contact d, normally bearing upon fixed contact d', through spring-contact e, bearing upon the fixed contact e', and 95 spring-contact f, bearing upon fixed contact f'. The circuit then passes through rheostat Rh and winding of unison-releasing magnet G to the arm H of a gang-switch from the contact of which the line extends. The vibrations of the polarized relay PR³ alternately close the local circuits of two escapement-magnets I I', which may be traced as follows: from one pole of the local battery LB' through the coil of escapement-magnet I to 100 stop p of the polarized relay, thence from the armature-lever of the polarized relay to the shaft K of the escapement-wheel L, and thence to the opposite pole of the battery. The circuit of the other escapement-magnet 105 is from the same pole of the battery LB' through the magnet I' to the stop p' of the polarized relay and thence through the armature-lever of the relay to the opposite pole of the battery. As the armature of the relay 110 vibrates between its stops in response to alternating currents received over the line the escapement-magnets are alternately energized, and the escapement-lever causes the 115 step-by-step rotation of the escapement-wheel. The shaft K of the escapement-wheel carries a contact-pin k, projecting radially therefrom and making contact successively with three contact-arms f' e' g'. The latter is the unison-contact, and when the 120 apparatus is rotated into the unison position the contact-pin k bears against contact g' and the armature-lever of polarized relay PR³ remains against its stop p, with the negative pole of the main battery to line. In this 125 130

condition of the apparatus a local circuit may be traced from the shaft of the escapement-wheel through pin k , contact g^2 , wire g' , arm H' of gang-switch, through the coil of an electromagnet of the clear-signal apparatus, which being charged the signal "clear" is displayed. This clear-signal apparatus may be of ordinary construction, comprising an electromagnet and an indicator actuated by the armature thereof and which when the magnet is energized is thrown in front of the opening in the box and displays the word "Clear." Thence the local circuit extends by wire g to one pole of local battery LB' , the opposite pole of which is connected to the shaft of the escapement-wheel. The escapement-wheel shaft and pin k move in the direction indicated by the arrow. The eleventh negative impulse over the line will have advanced pin k into contact with arm f^2 and the twelfth negative impulse into contact with arm e^2 . The thirteenth and fourteenth negative impulses would bring pin k into contact with the corresponding spring-arms in station 7. The unison-pin k being set to a given position on escapement-shafts K in the various stations, the contact-pins k , carried by said shafts, are set in suitable positions on the shafts. For instance, in station 1 the contact-pin k should be so placed that the first negative impulse will bring it into contact with a spring-arm at station 1 corresponding to spring-arm f^2 ; the second negative impulse will bring it into contact with arm e^2 at station 1.

The unison-release magnet G may be placed in circuit with the clear-signal magnet on local line g' and may be made use of to display the clear-signal as well as release the unison-pin. The unison-pin device S indicated may be the same as the well-known Edison unison device adapted to printing-telegraph and other electric apparatus. Assuming that the parts are in the position shown in the drawings, both in Figs. 1 and 2, and that the central-office operator desires to call station 6, the operator plugs, for instance, the left-hand hole in the switch 6 and removes the plug from unison-switch 15. The automatic operation of the apparatus thereupon commences, and reverse currents from the main battery are regularly sent into the line. When the trailer reaches the segment 6, the action of the escapement is arrested and the armature-lever of the relay PR pauses upon its contact y' , and the negative pole of the battery is to line. At the same time the armature-lever of the polarized relay PR^3 at station 6 pauses upon its contact p , and the contact-pin k on the shaft of the escapement-wheel at station 6 is arrested in contact with spring-arm f^2 . In this condition of the apparatus a local circuit from the battery LB' is completed as follows: from one pole of the battery to the shaft of escapement-wheel, pin k , arm f^2 , and coil of magnet F to opposite pole of the battery. The armature-lever of magnet F is attracted, its upper end lifts the contact-spring f from its contact-post f' , and the normal main-line circuit is interrupted, being now diverted from f , through the armature-lever of the magnet F , to wire f^3 , connected with one plate f^4 of a spring-jack, whose opposite plate f^5 is connected by wire f^6 with a contact-arm m of the return-signal apparatus, thence through the circuit-breaking wheel M , and by wire f^7 to the main line beyond the station. Two effects result from this action.

First, the armature-lever of the magnet F in being drawn forward completes a local circuit (indicated in dotted lines) containing a local battery and the coil of a magnet O . The armature-lever of this magnet being attracted releases a semaphore of an ordinary construction, which in dropping may close a local circuit for sounding an alarm, o representing a signal electric bell in such circuit. The semaphore and alarm may in railroad-work be either a danger or safety signal.

Second, the return signaling apparatus is set in operation to automatically send to the central office a signal which may be the number of the station. This is accomplished as follows: The lower end of the armature-lever of magnet F carries an insulated contact m' , which when the armature is attracted comes against a contact-post connected with one pole of the local battery LB' . The opposite pole of the battery is connected by wire g to a contact-post m^2 at the return-signal apparatus, upon which a contact-spring m^3 normally bears, and is connected with one terminal of the coil of the return-signal magnet N , whose opposite terminal is connected by wire m^4 with the insulated contact m' on the armature-lever of the magnet F . The magnet N being energized, its escapement armature-lever is attracted, and one of the pallets thereof drives the escapement-wheel N' one step, and a toothed wheel N^2 , moving with it, comes against a point n on contact-spring m^3 , pressing it out of engagement with the stop m^2 and interrupting the local circuit. Thereupon the escapement-lever is attracted by its spring, the other escapement-pallet drives the wheel another step, and the point n on the contact spring m^3 drops between the teeth of the ratchet-wheel, and the local circuit is reestablished. This operation being repeated, the escapement-wheel is advanced step by step, driving, by a pinion and gear-wheel N^3 , the circuit-breaking wheel M , which, revolving in contact with arm m , interrupts the main circuit six times at three equidistant points upon its periphery. Such return-signal may be received at the central office upon the sounder or Morse recorder. When the wheel M has made one revolution, a pin m^4 thereon comes against a spring m^5 and forces it into contact with a spring-con-

taet m^6 , the latter being connected, through wire g , with one pole of the local battery LB' . The spring m^5 is connected with a spring m^6 , that projects into the path of a 5 pin m^8 on the ratchet-wheel N' . At the time that the pin on the circuit-breaking wheel forces m^5 against m^6 pin m^8 comes into contact with spring m^7 , and a circuit of the local battery LB' is completed from m^6 10 through m^5 , m^7 , and m^8 , by wire m^9 through the coil of magnet N and by wire m^4 and insulated contact m' on the armature-lever of magnet F to the opposite pole of the battery. The return-signal apparatus is now held at 15 rest, the armature of magnet N remaining attracted until the armature-lever of magnet F is released on the station apparatus being disconnected from the main line, at which time the local circuit just traced is opened at 20 the contact m' , the escapement armature-lever of magnet N is retracted by its spring, and the escapement-wheel is advanced one step to carry the pin m^8 out of engagement with the contact-spring m^7 and restore the 25 apparatus to its normal condition. Station 6 having been called, the danger or safety signal displayed, and the return-signal sent to the central office, communication with the central office may be carried on by 30 means of any suitable telegraphic apparatus—for instance, by means of apparatus Q' , connected to the contacts of a jack-plug Q , which is shown out of the jack f^4 , f^5 , but which is designed to be normally inserted. 35 Of course the loop, including the apparatus Q' , may contain an ordinary relay and outfit.

To enable the operator at any station to call up the central or despatcher's office, the following arrangement is provided: When 40 the clear signal indicates that the line is free for use, the operator at any station may throw the gang-switch H , H' into the lower position, when the main-line circuit will be transferred through the switch-arm H and 45 wire h to the contact-arm m , resting on the return-signal wheel. At the same time the arm H' of the gang-switch is brought into connection with wire h' of a local circuit, which 50 may be traced as follows, the apparatus being at the unison-point and pin k in contact with spring-arm g^2 : from one pole of the local battery L , B' to pin k , contact-arm g^2 , wire g' , switch-arm H' , wire h' , through winding of escapement-magnet N , contact m^3 , its 55 contact-post m^2 , and wire g to the opposite pole of the battery. The return-signal mechanism is therefore set in operation, as hereinbefore described, and the characteristic station-signal is transmitted to the central office. On 60 receipt of the call the despatcher at the central office plugs either of the holes of the switch 6 , and thereupon the pole-changer at the central office is set in operation and the apparatus of the substation is introduced

into the circuit, as already described. The 65 movement of the apparatus at the various stations opens the local circuits at the points k , g^2 , through the magnet of the clear-signal apparatus, and thereupon a signal indicating that the line is in use is displayed. The calling-station may now communicate with the central office to the exclusion of all others. There is a possibility of two stations calling the central office at the same time or of a second station calling before the despatcher 70 at the central office has had opportunity to plug the switch of the station first calling, and in that event there would be a confusion of signals upon the recorder or other signal-receiving instrument at the central office. 75 Should this occur, the operator at the central office could send a general call to all the stations, as hereinafter described, ascertain which stations had called, and instruct them as to the order of their communication with 80 the central office. Should the despatcher at the central office desire or be required to place two or more of the stations on the line in communication with each other and with the central office, he may proceed as follows: 85 Assuming, for instance, that stations 6 and 7 are to be placed in communication with each other, the despatcher may first select one of the stations and instruct the operator there to hold his apparatus in position for communication. This might be conveniently effected in the following manner: The key or lever R when depressed mechanically holds the escapement-lever of the magnets I , I' in the position it assumes when the station has 90 been selected. The despatcher then calls the other station, and they are in communication with each other and with the central office. 95 Some suitable unison device for at any time running all the instruments to the unison-point is desirable. Where a station has 100 been called and the apparatus held mechanically, as just described, it will be thrown out of step or time with the apparatus at the other stations, and on completion of communication it is necessary to run all the apparatus to the unison-point. For this purpose the ordinary pin s and unison-worm S on the escapement-wheel, coöperating with armature-lever of unison-release magnet G , 105 may be employed. The magnet G is so constructed and wound that during the time the alternating impulses are traversing the line it is not charged sufficiently to attract its armature-lever, and consequently when the shaft S of the escapement-wheel at each station 110 has run to the unison-point it is arrested by the pin s , as is well understood. When this point has been reached, however, the action of the pole-changer is arrested at the central station because the unison-switch 115 has been plugged and the negative pole of the main battery is left to line, the magnet G is ener-

gized, its armature-lever attracted, and the unison released, the stop-pin s being drawn laterally to the initial position, as is well understood. The unison-magnet G might be placed in the local-circuit wire g' , extending from the contact-spring g^2 to the switch-arm H' , this circuit being open except when the instrument has been run to the unison-point and the contacts k g^2 brought together. This would be a desirable arrangement when working circuits of high retardation.

I have thus far described the selection of a station in the first position by plugging to the left-hand hole of the station plug-switch at the central office. If the despatcher desires to select a station—for instance, No. 3—with the apparatus thereof in the second position, which may be that in which a danger-signal should be automatically displayed, he plugs to the right-hand hole of the switch 3 at the central office. The escapement-wheel K is thus brought into a position in which the pin k comes in contact with the arm e^2 . The local circuit from the battery L B^2 through the coils of the magnet E is therefore completed, the armature-lever of the magnet is attracted, and the local connections established precisely as already described in connection with the completion of the circuit of the magnet F . The local circuit completed upon the movement of the armature-lever, as indicated in dotted lines, may contain an apparatus similar to O , or any other suitable apparatus, and on its completion may display a danger-signal, it being assumed that the signal that will be displayed when the magnet F attracts its armature is the safety-signal. Obviously the same signaling apparatus may be operated by both of these local circuits, one causing it to display a safety-signal and the other a danger-signal.

In the event of accident or any condition arising rendering it imperative for the operator at a station to call the central office without regard to the fact that the line is in use I have provided an emergency-call box located in the line at each station. This box may be similar to ordinary signal or messenger call-boxes, and when operated it is designed to give a special or emergency signal at the central station and the number of the station from which it is sent. For instance, the box at station 3 might send in the signal D Q 3, and the despatcher at the central office may thereupon instantly connect himself with the station. It is desirable to provide means whereby the despatcher at the central office may simultaneously introduce the instruments of all stations into the main line. When switch 16 at the central office is plugged, the armature-lever of the polarized relay there is arrested in contact with its stop z' , and the pole-changer is held in such position that the positive pole of the main battery remains to line. Consequently the

armature-levers of the polarized relays P R^3 at the different stations remain in contact with their posts p^2 . The escapement-magnet I' is therefore charged by the completion of the local circuit, and the escapement-lever is thrown thereby into the opposite position from that which it always assumes when a station has been individually selected, and the escapement-wheel is moved one step. The arrangement of contacts f^2 , e^2 , g^2 , and k is such that when the escapement-wheel is so held the point k cannot be in contact with either of the other contacts, and the circuits of magnets E and F cannot be completed. The armature of the polarized relay P R^3 when it comes to rest, as just described, with the positive pole of the main battery to line, comes against an additional contact-post T . Local circuit of a magnet U is completed as follows: from one pole of the local battery L B^2 to the armature-lever of the polarized relay, its contact T , through the coil of the magnet U to the opposite pole of the battery. The magnet attracts its armature-lever, which lifts spring-contact d from its contact-post d' , and the main-line circuit is opened at this contact and transferred, through the armature-lever and wire u , to one jaw u' of a spring-jack, the other jaw u^2 of which is connected by wire u^3 to the switch-arm H . The spring-jack u' u^2 may have plugged to it any suitable telegraphic apparatus, such as hereinbefore suggested. The armature-lever of the magnet U when attracted also completes a local circuit u^3 , indicated in dotted lines, which may contain a semaphore or other apparatus that calls the operator's attention to the fact that a general call has been sent from the central office.

Of course it is to be understood, as described in connection with the unison-magnet, that neither of the magnets U , E , and F are sufficiently charged by the brief completions of their local circuits during the regular vibrations of the polarized-relay armature and the regular step-by-step motion of the escapement mechanism; but when the apparatus is arrested with the negative pole of the battery remaining to line the magnet E or F is charged at any station selected and attracts its armature-lever, and when the armature-lever of the polarized relay P R^2 comes to rest with the positive pole of the battery to line the magnets U at all stations are sufficiently charged to attract their armature-levers and effect the operation already described.

In circuit with the magnet G at each station is an adjustable rheostat R_h . It is designed that the normal resistance at each station, including the polarized relay, rheostat, and magnet G , shall equal substantially the resistance of the circuit when the instruments at the station are connected in the circuit for communication at the central office.

I claim as my invention—

1. The combination of the pole-changer, the relay, the lever carrying the pole-changer, the magnets controlling the lever, the escape-
5 ment device, two series of alternating contact., switching devices with which the contacts of one series are respectively connected, a switching device with which the contacts of the other series are connected, a trailing con-
10 tact-maker, operating and connecting with the two series of contacts, and the local circuits, substantially as described, whereby the pole-changer may be brought to rest in one position to leave a given pole of the battery
15 to line, with the trailing contact-maker in contact with the desired contact of one series, and may be brought to rest with the opposite pole of the battery to line, and the trailing contact-maker in contact with any one of the
20 contacts of the other series substantially as set forth.

2. The combination of two series of contacts; a switch device having contacts for each of the two adjoining contacts in one series, circuit connections between each contact and its corresponding switch-contact, a switch device with which all the contacts of the other series are connected, a contact-
25 maker for successively making contact with
30 all the contacts of the two series, the controlling-magnet C C', the local circuits, and the polarized relay substantially as set forth.

3. The combination of a main battery, a line, a pole-changer for sending reverse currents to line, means for bringing it to rest, after the transmission of any given number of impulses, with a given pole of the battery to line, a series of stations connected with the line and each having a polarized relay in the
35 line, two local circuits controlled at the stops of said relay, a magnet in each circuit, the magnets of the two circuits being alternately energized, apparatus at said station actuated step by step by said magnets, contacts con-
40 trolled by said apparatus, and adapted to be brought into connection upon transmission of a given number of alternating impulses be-
45 ing sent over the line, a local circuit controlled at said contacts including a magnet,
50 an armature for said magnet, a local circuit controlled thereby, and automatic return-
55 signal apparatus included in said local circuit, whereby when the apparatus has been brought into proper condition or position a return-signal is transmitted to the central office, substantially as set forth.

4. The combination of a main battery, a line, a pole-changer for sending reverse currents to line, means for bringing it to rest, after the transmission of any given number of impulses, with a given pole of the battery to line, a series of apparatus at different stations connected with the line and each having a polarized magnet in the line, local de-
65 vices controlled by the magnet at each sta-

tion for effecting the step-by-step movement of the apparatus at all of said stations in correspondence with the impulses sent over the line and the arrest of the apparatus at one of said stations after a predetermined number of impulses corresponding with the selection of said station has been transmitted over the line, telegraphic instruments at each station, and local connecting apparatus whereby the normal circuit of the line at the selected station is directed through said telegraphic instruments, so that a central-office operator may select any station for communication.

5. The combination of a main battery, a line, a pole-changer for sending reverse currents to line, means for bringing it to rest, after the transmission of any given number of impulses, with a given pole of the battery to line, a series of stations connected with the line and each having a polarized magnet in the line, local devices controlled by the magnet at each station, apparatus at all of said stations actuated step by step by said devices in correspondence with the impulses sent over the line and the arrest of the apparatus at one of said stations after a predetermined number of impulses corresponding with the selection of said station has been transmitted over the line, telegraphic instruments at each station, local connecting apparatus whereby the normal circuit of the line at the selected station is directed through said telegraphic instruments, and automatic return-signal mechanism through which the line is also directed, whereby the central-
60 office operator may select any station for communication, and a return-signal from the selected station be sent to indicate that the proper station has been selected.

6. The combination of a line having connected therewith a central or despatching station and a number of substations, a main battery, a pole-changer at the central station for sending alternating currents to line, means for bringing it to rest, after the transmission of any given number of impulses, with a given pole of the battery to line, apparatus at each station for responding step by step to said impulses, means whereby when the apparatus at any station has been advanced a particular number of predetermined steps the main-line circuit is directed through telegraphic instruments at said station, automatic return-signal devices through which the line-circuit is also then directed, and apparatus at the central station for receiving such automatic return-signal, whereby when a station has thus been selected an automatic signal indicating the fact is received at the central office.

7. The combination of a line having connected therewith a central or despatching station and a number of substations, a main battery, a pole-changer at the central station for sending alternating currents to line, means

for bringing it to rest, after the transmission of any given number of impulses, with a given pole of the battery to line, apparatus at each station for responding step by step to said impulses, means whereby when the apparatus at any station has been advanced a particular number of predetermined steps the main-line circuit is directed through telegraphic instruments at said station, automatic return-signal devices through which the line-circuit is also then directed, and apparatus at the central station for receiving such automatic return-signal, whereby when a station has thus been selected an automatic signal indicating the fact is received at the central office, and a local circuit including signaling apparatus and means for controlling the same when the station has been selected and its telegraphic apparatus included 20 in the line-circuit.

8. The combination of a line having connected therewith a central or despatching station and a number of substations, a main battery, a pole-changer at the central station for sending alternating currents to line and adapted to be brought to rest, after the transmission of any given number of impulses with a given pole of the battery to line, apparatus at each station for responding step by step to said impulses, means whereby when the apparatus at any station has been advanced a particular number of predetermined steps the main-line circuit is directed through telegraphic instruments at said station, a resistance in the normal line-circuit at each station equal to the resistance of the telegraphic instruments introduced into the line, and means for eliminating said resistance from the direct line-circuit when the telegraphic instruments are introduced thereinto.

9. The combination of a line having connected therewith a central or despatching station and a number of substations, a main battery, a pole-changer at the central station for sending alternating currents to line, means for bringing it to rest, after the transmission of any given number of impulses, with a given pole of the battery to line, apparatus at each station that responds to the alternating currents, means for arresting said apparatus at a given station in either of two positions each of which is determined by a predetermined number of impulses transmitted from the central station, means for introducing into the line-circuit telegraphic or other instruments when the apparatus is arrested in either position, and means locally actuated at said station to display one signal when the apparatus is arrested in one position and another signal when the apparatus is arrested in the other position.

10. A telegraphic or signaling system comprising a main line, a central and sub stations thereon, a main battery, a pole-changer at the central station for sending alternating currents to the line, means for bringing it to rest, after the transmission of any given number of impulses, with a given pole of the battery to line, apparatus at each station that moves step by step in response to said impulses, means whereby when the apparatus at any station has thus been advanced a particular number of predetermined steps the main-line circuit is directed through telegraphic apparatus at said station, the connections at other stations not being so changed, whereby any substation may be selected for communication with the main office, means at the central office whereby the pole-changer may be brought to rest with the opposite pole of the main battery to line, and apparatus at each substation for introducing into the line at each station telegraphic instruments whenever the last-mentioned pole of the battery is left to line, whereby the central office may simultaneously connect all stations on the line for communication.

11. A telegraphic or signaling system comprising a main line, a central and sub stations thereon, a main battery, a pole-changer at the central station for sending alternating currents to line, means for bringing it to rest, after the transmission of any given number of impulses, with a given pole of the battery to line, apparatus at each station that moves step by step in response to said impulses, means whereby when the apparatus at any station has thus been advanced a particular number of predetermined steps the main-line circuit is directed through telegraphic apparatus at said station, the connections at other stations not being so changed, whereby any substation may be selected for communication with the main office, means at the central office whereby the pole-changer may be brought to rest with the opposite pole of the main battery to line, and apparatus at each substation for introducing into the line at each station telegraphic instruments whenever the last-mentioned pole of the battery is left to line, whereby the central office may simultaneously connect all stations on the line for communication, and an emergency-call box at each station for sending special signals or calls to the central office.

In testimony whereof I have hereunto subscribed my name.

ROBERT J. SHEEHY.
